UNITED STATES PATENT OFFICE.

GEORGE HAND SMITH, OF CHELSEA, COUNTY OF MIDDLESEX, ENGLAND.

APPARATUS FOR STAINING AND COLORING.

SPECIFICATION forming part of Letters Patent No. 292,221, dated January 22, 1884.

Application filed August 20, 1883. (No model.)

To all whom it may concern:

Be it known that I, GEORGE HAND SMITH, of Rochester, in the county of Monroe and State of New York, a citizen of the United States of America, now residing at Chelsea, in the county of Middlesex, England, doctor of medicine, have invented certain new and useful improvements in means or apparatus employed in coloring, printing, or producing colors or shades of colors, or designs, in or upon animal, vegetable, and mineral substances; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The improvements have reference to means or apparatus adapted to facilitate the operation of coloring, printing, ornamenting, or the production of colors or shades in or upon animal, vegetable, and mineral substances—such as marble, stone, terra-cotta, bone, ivory, wood, india-rubber, and others—by subjecting those substances, when the desired marks, designs, or coloring-matters have been applied thereto, to first a dry or relatively dry atmosphere of suitable temperature, in a closed chamber, and then to a vapor of slightly higher temperature than the substances treated, and whereby such difference of temperature is capable of being maintained for a sufficient period, the rate of increase of that difference of temperature being dependent upon the nature and other conditions of the objects treated, in order to cause the sinking of the coloring-matter or design or marks into the substances, and also to provide means of adjusting or regulating the amount of heat employed both in the drying portion of such process and in producing or inducing penetration of the color or substance adapted to produce color or such like matter, as well as to facilitate application to and removal from the operating-chambers of the matters treated. For this purpose I provide a central or inner chamber surrounded on all four sides and top by two or more air-chambers—one without the other—to prevent radiation, and outside I provide suitable wood or other non-conducting substance with

intervening packing of hair or the like matters adapted to further prevent radiation or loss of heat. One or more than one side of this inner chamber may be formed with or as a door or opening, and corresponding doors or openings are likewise formed in the surrounding walls or sides of the heat-retaining air-chambers, to allow of access to and removal and replacement of the contents of that inner chamber. The walls or sides of the inner or operating chamber rest within a tray or trough or shallow recess adapted to contain at the desired time a suitable liquid, such recess being formed in or over a closed water or liquid chamber, which closed chamber, with its contained liquid, is heated below by gas-jets or other suitable source of heat, capable of being readily controlled by valves or such like means. The walls or sides of the surrounding air-chambers also dip into and have their communication one with another, and with the inner chamber sealed or cut off by dipping into the liquid in this recess when such is supplied. Holes formed below the liquid-level of the trough or recess permit circulation freely of such liquid within the trough. A suitable non-conducting packed cover or casing surrounds the exterior air-chamber. The heat from the gas-jets or other heating means is prevented from passing away too freely by means of suitable curtains or inclosing-walls below the underneath side of the closed heating-chamber. The temperature of the inner chamber, and also of the closed liquid-heating chamber, is indicated by thermometers placed in communication with those chambers.

In use the substances to be colored or marked or otherwise operated upon, as already described, are placed in the inner chamber; the opening or openings closed. This chamber is then ready within the inclosing air-chambers, and the close-fitting doors or covers to these are closed, respectively, cutting off atmospheric communication between them, and the outer casing or packed cover is also made entire by closing the opening thereto. Heat being then applied by the gas or other heater below the closed liquid-chamber, heat is imparted to the inner chamber in turn for the desired time as a dry or relatively dry heated atmosphere around the substances to be colored, marked, printed, or similarly treated, to

sink or induce impregnation of the color or matter to produce color or marking therein. A valve or valves or other suitable means are operated, controlling a supply of a suitable liquid from suitable pipes or conduit in connection with the closed liquid-heating chamber, so as to cause a limited quantity of water or other liquid to be more or less slowly spread over the floor of the chambers, cutting off atmospheric communication, as already mentioned, between them. The vapor now produced is maintained at a slight difference of heat above that of the articles treated within the inner chamber of from $\frac{1}{10}^{\circ}$ to 2° , or thereabout, so as to preserve a differential temperature between such surrounding atmosphere and the articles operated upon sufficient to insure satisfactory results, but not sufficient to cause injurious deposit of moisture thereon, as such condensation would be detrimental to the object in view—viz., penetration of the color or colored design or color-producing agent into the substance of the goods or articles—and therefore it is essential that the control of the relation of the respective temperatures be readily adjustable to a nicety, and this is furthermore insured by suitable regulators and valves applied to the gas-supply pipes to the pipe of supply of heated water to the floor of the chambers, and by a supply of cold water suitably controlled by valves in connection with the closed liquid-heating chamber beneath the floor of the inner chamber, so as to be available for reducing any excess of temperature in the water contained therein, and consequently the temperature of the inner chamber.

In some instances it is not requisite for the liquid supplied to the floor of the inner chamber to have any communication with or to flow into the lower parts of the air-chamber surrounding such inner chamber.

The liquid-heating chamber below the floor may be in some cases carried a greater or less distance up the outer sides of the air-chambers surrounding the inner receptacle to give sufficient head or cause sufficient pressure for the flow of the liquid over such floor.

In some instances—as for large pieces of marble—it may be advantageous or more convenient first to heat the marble in a separate heating-chamber or apparatus by applying heat more directly. In such cases, for safety, the marble or other such large articles should be heated a little higher than the operating-chamber, so as to be safe from any ill effects of condensation from cooling in transferring.

In operation with this apparatus the rate of increase at which I find the relative temperatures of the vapor and the articles being treated should rise, and the time for which such temperature should be maintained, depends on the nature of the material and the thickness of the articles—for instance, a thick piece of marble, ivory, or other substance will require a considerably slower rate of increase per hour than would be satisfactory for

a thin sheet of the same material. The heat must be allowed greater time to penetrate the greater thickness or substance, and the rate of increase of temperature must be correspondingly lessened. For instance, while for some thin or quickly-penetrated substances a rate of increase of temperature of the vapor in the operating-chamber and of the liquid-heating chamber of, say, 30° per hour may be advisable and give good results, on the contrary, for much thicker bodies, an increase of one-tenth of a degree per hour may be as fast a rise as may safely be permitted, regard being had to the avoidance of condensation of moisture on the goods being heated, as already more fully described. Thus, articles of ivory of one-fourth of an inch in thickness I have found to give a satisfactory result when thus treated at a relative increase of 5° Fahrenheit per hour, the coloring-matter employed being, say, one of the ordinary aniline colors; and when employing as a coloring-matter sulphate of iron, and operating therewith on the surface of a piece of marble of one inch in thickness—say, starting at a temperature of 130° , at the rate of increase of temperature of $\frac{1}{2}^{\circ}$ to 2° per hour—that, after about eighteen hours' treatment, such as described, good results were attained.

In the drawings, Figure 1 is a longitudinal section of the apparatus. Fig. 2 is a transverse section of one-half of the same divided down the center by the line xx of Fig. 3. Fig. 3 is a sectional plan view thereof. a indicates the central or operating chamber for containing the objects to be treated, as described.

b and c are surrounding air or heat retaining cells or chambers.

d is an outside double wall to the cell c , packed or lagged with hair or other suitable non-conductor, the inner skin, d' , being metal and the outer skin, d'' , wood.

e represents the water bath, across which lie supports e' for the chamber a , having holes e'' pierced therein, to facilitate circulation of the liquid in that chamber e .

a' represents a tray or trough for the reception of a limited quantity of water to be let in from the water bath e , when required, by means of a valve or cock, f , when operated by the wheel f' .

a^2 is a door in the surrounding wall a^3 to the chamber a ; b^2 , a door in the surrounding wall b^3 to the chamber or cell b , and c^2 the like door in the wall d for the chamber c .

a^5 is a portion of a grating to cover the lower part of the chamber a above the bottom or tray portion a' .

g are burners for heating the water bath e by gas supplied by pipes g' .

g^2 is a gage for regulating the flow of gas.

$h h' h^2$ are thermometers for indicating the heat, respectively, of the inner chamber, d , the air chamber or cell b , and the water bath e .

i is the inlet-pipe for supply, and j the outlet for liquid to the water bath e .

The roofs a^4 , b^4 , and d^4 are formed sloping, as shown, in order to carry down any moisture condensed thereon.

In operation, the doors a^2 , b^2 , and c^2 being closed, the gas-burners g heat the water bath e , which in turn heats the air-cells b and c and the central chamber, a . When vapor is desired in the chamber a , liquid from the water bath e is let in by cock f , turned by handle f' , and liquid flows over the tray a' and vapor arises into the chamber a . Should the heat of the water bath e be required to be lowered, cold water can be let in by pipe i and heated water let out by the pipe j . The thermometers h and h^2 , indicating, respectively, the relative temperatures of the chamber a and water bath e , enable the heat of that bath, and consequently that of the vapor or atmosphere in the chamber a , to be regulated to a great nicety. The desired heating having been maintained and completed, as desired, the doors c^2 and b^2 to the air-cells and the door a^2 to the operating-chamber may be opened, and the objects treated removed or the operation repeated.

Having thus fully described my invention and the manner in which the same is to be employed, I would have it understood that what I claim is—

The combination, in apparatus employed in coloring, printing, or producing colors or shades of colors or designs in or upon animal, vegetable, and mineral substances, of an inner operating-chamber, a , with doors a^2 , liquid-tray a' , water bath e , with outlet and supply there- 30 to, the surrounding heat-retaining air cells or chambers b and c , with doors b^2 and c^2 , and walls b^3 c^3 , water-cock f , gas-burners g , or their equivalents, and means for regulating heat applied, all substantially as and for the purpose 35 described. 40

In testimony whereof I affix my signature in the presence of two witnesses.

GEORGE HAND SMITH.
